COUNTERBORING-TOOL.

1,312,033.

Patented Aug. 5, 1919.

Application filed January 24, 1918. Serial No. 213,576.

To all whom it may concern:

Be it known that we, MURRAY J. HUGGINS and RICHARD B. HUGGINS, citizens of the United States, residing at Bridgeport, Conn., and Middletown, N. Y., respectively, in the counties of Fairfield, Connecticut, and Orange, New York, respectively, have invented certain new and useful Improvements in Counterboring-Tools, of which the following is a specification.

This invention relates to improvements in counter boring tools.

The object of the invention is to construct a simple and efficient tool of this character which may be secured in the clamp employed for holding the counter boring tool of a punching machine or not, as desired.

Another object is to provide improved means for controlling the position of the counter boring tool thereby governing the depth of the counter bore.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a plan view of the tool constituting this invention with the cover plate removed.

Fig. 2 is a transverse section taken on the line 2—2 of Fig. 1.

Fig. 3 is a longitudinal central section taken on the line 3—3 of Fig. 1, and

Fig. 4 is a detail sectional view taken on the line 4—4 of Fig. 1.

Fig. 5 is a detail view of gage 31.

In the embodiment illustrated the device constituting this invention comprises a base plate 1 having vertically adjustable supporting legs 2, any desired number of which may be employed, four being here shown, and it may be secured to the work by any suitable means. These legs are held in adjusted position to prevent accidental turning thereof by lock nuts 3. This base plate 1 is preferably substantially rectangular in form and tapers toward one end, being provided at its small end with a gear retaining seat or socket 4 and alined with this seat

are a plurality of annular gear seats 5, three of which are here shown, the two foremost being substantially of the same size and the rearmost being larger. Mounted to rotate in these seats 5 are a plurality of gears 6 and a smaller gear 7 is positioned in the gear seat 4, all of said gears meshing and adapted to be simultaneously turned by means presently to be described.

A larger gear seat 8 is formed in alignment with the seat 5 and is designed to receive a gear 9 carried by a driving shaft 10 through which the train of gears is designed to be driven.

The journals on which gears 6 are mounted are here shown in the form of screws 11 which pass through the central openings in said gears and detachably engage threaded bores 12 formed in the base plate as is shown clearly in Fig. 3.

A shaft 13 extends through gear 7, being fixed to turn therewith and carries on its lower end the cutting tool or bit 14 which is fixed to move with said shaft. As shown, this shaft where it passes through the base plate 1 is reduced in size, although it need not necessarily be so formed, and is provided at its upper end with a head 15 between which and the upper face of gear 7 is disposed a coiled spring 16, the gear being shown provided with a seat 17 to receive this spring.

A rocking lever 18 is fulcrumed by means of a shaft 19 in two uprights 20 which have threaded engagement with the base plate on opposite sides of the train of gearing, said uprights being arranged in transverse alignment and having openings in their upper ends to form bearings for the shaft ends 21 which are reduced and have shoulders 22 at their inner ends.

One end of this lever 18 extends over and engages the head 15 of shaft 13, while its other end has an opening or socket 23 formed therein and extending from one side edge to the other thereof, being designed to receive one end of a feed lever 24. The coiled spring 16 on shaft 13 operates to normally hold said shaft in raised position against the under face of lever 18 thereby rocking said lever and holding its other end in lowered position as shown in Fig. 3. This spring also holds the cutting tool 14 in raised position against the lower face of plate 1.

The feed lever 24 is fulcrumed in an upright 25 swiveled on the base plate 1, said upright having its upper end shown bifurcated to receive said lever. The front end 5 of said lever is twisted as shown at 26 to position its terminal in a plane at right angles to its body portion and this terminal 27 has its free end inclined transversely as shown at 28 and is preferably provided on each 10 face with a rib 29. This lever is designed to be inserted sidewise into the socket 23 at the rear end of the rock lever 18 as is shown clearly in Figs. 1 and 3 and is held against accidental disengagement therefrom 15 by means of the rib 29.

This lever 24 has a hand grip 30 at its outer end, the fulcrum of said lever being positioned much nearer its front than its rear end so that a greater leverage may be 20 obtained for actuating the rock lever 18 against the tension of spring 16 for lowering the cutting tool 14. It is to be understood that this lowering of the cutting tool provides for the extension or increase in the 25 depth of the counter bore formed thereby.

A gage 31 is carried by the base plate 1, being adjustably mounted therein, the shank thereof being shown threaded for engagement with a threaded bore 32 extending 30 through a base plate 1. This gage 31 is in the form of an upright having a laterally extending arm 33 at its upper end which is designed to be positioned in the path of the feed lever 24 for limiting the upward movement of its front end for regulating the raising of the socketed end of lever 18 and the depression of the cutting tool 14.

A cover plate 34 is preferably arranged over the upper face of the base plate 1, extending 40 under lever 18 and which is secured to said base plate in any suitable or desired manner, said cover plate being designed to protect the train of gearing from dust and the like.

In the use of this device, the shaft 10 being 45 rotated from any suitable source of power, operates to drive the train of gearing and thereby rotate the cutting tool 14 which is designed to form a counter bore in the work operated upon. To increase the depth of the bore so formed, the operator grasps the handle 30 of the feed lever 24 and forces it downwardly thereby elevating the socketed 50 end of the rock lever 18 lowering its opposite end, thus forcibly depressing the cutter shaft 13 against the tension of the spring 16 and causing said cutter to increase the depth 55 of the bore being formed. The gage 31 is preferably first adjusted so as to regulate or limit the depth that the tool 14 may be lowered in the manner above described.

From the foregoing description, taken in connection with the accompanying drawings, the advantages of the construction and of 65 the method of operation will be readily ap-

parent to those skilled in the art to which the invention appertains, and while we have described the principle of operation of the invention together with the device which we now consider to be the best embodiment 70 thereof, we desire to have it understood that the device shown is merely illustrative and that such changes may be made as are within the scope of the claimed invention.

We claim:—

1. In a device of the class described, a base plate, a shaft extending therethrough, a cutter fixed to said shaft and positioned on one side of said base plate, a spring mounted on said shaft on the other side of said base plate 80 and adapted to hold said cutter in close proximity to said base plate, a rocking lever having one end positioned over said shaft for moving it against the tension of said spring, and a feed lever fulcrumed on said 85 plate and adapted to engage said rocking lever for actuating it to project said cutter.

2. In a device of the class described, a base plate having a plurality of seats formed in one face thereof and communicating with each other, gears mounted in said seats and meshing with each other, a shaft carried by one of said gears and extending through said base plate, a cutter fixed to said shaft on the face of said plate opposite to that in 95 which said seats are formed, a stop on the other end of said shaft, a coiled spring mounted on said shaft between said stop and the gear carried thereby, means for actuating said gears to rotate said cutter, and 100 means under the control of the operator for projecting said shaft against the tension of said spring to vary the depth of the bore formed by the cutter.

3. In a device of the class described, a base 105 plate having a plurality of seats formed in one face thereof and communicating with each other, gears mounted in said seats and meshing with each other, a shaft carried by one of said gears and extending through 110 said base plate, a cutter fixed to said shaft on the face of said plate opposite to that in which said seats are formed, a stop on the other end of said shaft, a coiled spring mounted on said shaft between said stop and 115 the gear carried thereby, means for actuating said gears to rotate said cutter, a rocking lever positioned above said base plate and having one end arranged over said shaft to engage the head thereof and its other end 120 provided with a socket, a feed lever fulcrumed above the base plate and adapted to engage said socket whereby on the movement of the feed lever said rocking lever will be actuated to project said cutter against 125 the tension of its spring.

4. In a device of the class described, a base plate, vertically adjustable legs engaged therewith, a rocking lever fulcrumed on said plate in a plane above one face thereof, a 130

spring retracted cutter having a shaft positioned in the path of one end of said lever, a swiveled standard mounted on said plate, a feed lever fulcrumed on said standard, co-operating means carried by adjacent ends of said levers for co-operative engagement, a train of gearing connected to rotate said cutter, and means for actuating said gearing.

5. In a device of the class described, a base plate, adjustable legs engaged therewith, means for locking said legs in adjusted position, a shaft extending through said plate and having a cutter fixed to one end thereof and a gear to its other end, a stop 10 carried by said last mentioned end at a point spaced from said gear, a coiled spring mounted on said end between said stop and gear, the shaft being slidable in said gear but rotatable therewith, a train of gears connected to actuate said shaft carried gear, and means under the control of the operator 15 for projecting said shaft against the tension of its spring for regulating the cutting depth of the cutter.

20 6. In a device of the class described, a base plate, adjustable legs engaged therewith, means for locking said legs in adjusted

position, a shaft extending through said plate and having a cutter fixed to one end thereof and a gear to its other end, a stop 30 carried by said last mentioned end at a point spaced from said gear, a coiled spring mounted on said end between said stop and gear, the shaft being slidable in said gear but rotatable therewith, a train of gears connected to actuate said shaft carried gear, a 35 rocking lever having one end positioned to engage said shaft and its other end provided with a socket opening through its side edges, a feed lever fulcrumed on said base plate 40 and swiveled to move in a horizontal plane, said feed lever having one end flattened and beveled at its terminal for interlocking engagement with the socket of said rocking lever whereby on the actuation of said feed 45 lever said rocking lever is operated to project said cutter.

In testimony whereof we affix our signatures in presence of two witnesses.
